POWER-OPERATED CARVING KNIFE

Fritz Bremshey and Wolfgang Fülling, both of Solingen-Ohligs, Germany, assignors to Bremshey & Co., Solingen-Ohligs, Germany, a firm

Filed Feb. 1, 1966, Ser. No. 853

Term of patent 14 years

(Cl. D95—3)

FIGURE 1 is a top plan view of a power-operated carving knife showing our new design;

FIGURE 2 is a side elevational view thereof, the other side being similar in appearance;

FIGURE 3 is a bottom plan view thereof; and

FIGURE 4 is an end view thereof of the end with the blade, the other end being conventionally flat.

We claim:

The ornamental design for a power-operated carving knife, as shown and described.
